HOLDER FOR A COLLAPSIBLE TUBE

Victor J. Bardon, 313 N. Kenton Ave.,
Los Angeles, Calif.

Filed Feb. 17, 1964, Ser. No. 78,650

Term of patent 14 years

(Cl. D4—3)

FIG. 1 is a perspective view of a holder for a collapsible tube showing my new design;
FIG. 2 is a side elevational view;
FIG. 3 is a rear elevational view;
FIG. 4 is a bottom plan view;
FIG. 5 is a front elevational view;
FIG. 6 is a top plan view.
I claim:

The ornamental design for a holder for a collapsible tube, substantially as shown.
